UNITED STATES PATENT OFFICE

THOMAS R. BARMES, OF VINCENNES, INDIANA.

DRAFT-EQUALIZER.

No. 826,011.

Specification of Letters Patent.

Patented July 17, 1906.

Application filed January 23, 1906. Serial No. 297,403.

7. all whom it may concern:

Be it known that I, THOMAS R. BARMES, a citizen of the United States, residing at Vincennes, in the county of Knox and State of Indiana, have invented certain new and useful Improvements in Draft - Equalizers, of which the following is a specification.

My invention relates to draft-equalizers of the class in which a relatively short lever projecting laterally from one side of the tongue or pole is pivotally connected with a longer lever jointed to the tongue and projecting laterally from the opposite side thereof and in which two horses on opposite sides of the tongue are connected to the shorter lever, while one or two horses are connected to the outer end of the longer lever. Such draft-equalizers are commonly employed in self-binding harvesters, where the space for the team on one side of the tongue is limited, there being room for only one horse, while it is necessary in order to draw such machines that three or four horses be hitched to it.

The object of my invention is to provide means for connecting the parts together, so that the horses may be kept in proper position, side draft avoided, and the parts may be operated easily and efficiently.

In the accompanying drawings, Figure 1 is a perspective view of my improved draft-equalizer with the parts in one position. Fig. 2 is a perspective view thereof with the parts in a different position.

The longer lever A on the off side of the tongue is pivoted at *a* to the tongue B, while the short lever C is pivoted at *c* to the lever A between its outer end and its pivot. To the outer end of the lever is connected, by means of a clip K, a doubletree or whiffletree D, carrying swingletrees E, and to the shorter lever C is pivotally connected a curved arm F, to the front end of which is connected a doubletree or whiffletree G, carrying swingletrees H. The outer end of the long lever A is connected to the outer end of the short lever C by a chain I, passing around a pulley J on the tongue in rear of the pivot *a*. Of course rods may be substituted for a part of the chain, as indicated at *i*; but that part of the connection which passes around the pulley J, should be chain or similar flexible connection.

I have shown a four-horse evener; but the connection between the whiffletree D and the lever A may be adjusted by changing the position of the clip K. In the drawings the

clip is shown as secured in position by a bolt *k*, and I have indicated an additional hole *k'* to provide for the proper adjustment. The chain I is attached to an eyebolt L at the outer end of the lever A, and I have shown an additional eyebolt L' to provide for the proper adjustment. In this way I may change to a three-horse evener.

The arm F is one of the most important parts of my invention. It will be observed that it is curved and has a short arm *f* and a long arm *f'*. The end of the short arm is pivotally connected to the outer end of the lever C, while the end of the long arm is pivotally connected with the whiffletree G. The arm extends rearwardly from the pivot, then laterally, and then forwardly in line with the tongue. Preferably the arm F is composed of two members of the same shape, one above the lever C and the other below it. In this way the connection between the whiffletree G and the lever C is such as to keep the horses in line on opposite sides of the tongue. The pivotal connection between the whiffletree G and the arm F may always be substantially in line with the tongue. Thus the team is kept in proper position and side draft is avoided. In other respects the evener is constructed and operated like others of its class. I have shown the pulley J is mounted on the upper side of the tongue; but it may be located on the under side thereof.

I claim as my invention—

1. A draft-evener comprising a tongue; a long lever pivoted to the tongue and projecting laterally from one side thereof, a short lever projecting from the opposite side of the tongue and pivoted to the longer lever between its outer end and its pivot, a flexible connection between the outer ends of the two levers, an arm pivoted to the outer end of the shorter lever, and having its outer end in line with the tongue, a whiffletree pivotally connected with the outer end of the arm, and a whiffletree pivotally connected with the outer end of the longer lever.

2. A draft-equalizer of the class in which long and short levers project from opposite sides of the tongue, and are pivotally connected with the tongue and with each other, a flexible connection between the outer ends of the levers, a whiffletree connected with the outer end of the longer lever, an arm projecting toward the tongue from the outer end of the shorter lever, and a whiffletree connected to the outer end of this arm.

3. A draft-equalizer of the class in which long and short levers project from opposite sides of the tongue, and are pivotally connected with the tongue and with each other, a flexible connection between the outer ends of the levers, a whiffle-tree connected with the outer end of the longer lever, a curved arm pivotally connected with the outer end of the shorter lever, projecting rearwardly therefrom, then inwardly toward the tongue and forwardly in line with the tongue, and a whiffle-tree pivotally connected with the outer or front end of said arm.
4. The combination of a tongue, a long lever pivotally connected therewith and projecting laterally from one side of the tongue, a shorter lever projecting laterally from the

opposite side of the tongue and pivotally connected with the longer lever, a pulley on the tongue in rear of the levers, a chain passing over the pulley and connecting the outer ends of the two levers, a curved arm pivotally connected with the outer end of the shorter lever and having its outer or front end over the tongue a whiffle-tree adjustably connected with the outer end of the longer lever and a whiffle-tree connected to the outer end of the short lever.

In testimony whereof I have hereunto subscribed my name.

THOMAS R. BARMES.
